UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

RECORDING MECHANISM.

1,195,608.

Specification of Letters Patent. Patented Aug. 22, 1916.

Application filed August 13, 1912. Serial No. 714,822.

To all whom it may concern:

Be it known that I, FRANK C. RINSCHE, a citizen of the United States, residing at Detroit, in the county of Wayne and State 5 of Michigan, have invented certain new and useful Improvements in Recording Mechanisms, of which the following is a specification.

The present invention relates to recording mechanisms for adding machines which provide for separately listing items upon independent strips or sheets of paper, and may be regarded as an improvement upon the invention of Jesse G. Vincent, disclosed 15 in Patent No. 968,005, issued August 23rd, 1910, to Burroughs Adding Machine Company. In that Vincent patent a laterally shiftable paper carriage is shown carrying two roller platens axially alined but independently rotatable, having separate line-spacing mechanisms. While it would be possible to actuate both line-spacing mechanisms of that Vincent machine simultaneously and so turn the two platens as one, the 25 Vincent arrangement was not designed with that end in view, and so included no special equipment for converting the machine at will from a single platen to a duplex platen condition.

One object of the present invention is to provide for employing the platen structure in sections or as a single platen, at the will of the user of the machine, to which end, in the construction here shown, the sections of 35 the roller platen are closely assembled and a coupling is provided for uniting them rotatably.

Another object of the present invention is to prevent the possibility of any mis-operation or locking-up of the parts by reason 40 of the shifting of the carriage while an operation of the machine proper is in progress. To this end, in the construction here shown, a locking device is provided for engaging 45 the carriage during the operation of the machine proper whenever the carriage occupies a position where the inner end portion of either of two line-spacing bail-rods is embraced by the jaws of the line-spacing 50 slide, which is reciprocated by an element of the machine proper in the customary manner.

With the above stated objects in view, the invention consists in certain novel features 55 of construction and combinations of parts,

the essentials of which are recited in the appended claims, and a preferred form of embodiment is illustrated in the accompanying drawings, described in detail hereinafter.

Of said drawings Figure 1 represents in 60 rear elevation partly broken away an adding machine equipped with mechanism embodying my invention; Fig. 2 is a sectionalized side elevation of the paper carriage equipment and coöperating parts of 65 the machine; Fig. 3 is a fragmentary rear elevation illustrating a changed condition from that illustrated in Fig. 1; Fig. 4 is a sectionalized top plan view of the platen structure; Fig. 5 is a horizontal section on 70 a lower plane; Figs. 6 and 7 are detail perspective views.

I have not considered it essential to illustrate or describe the adding machine proper, since the present invention is not concerned 75 with adding functions. However, I may state that the invention is here shown adapted to the well-known Burroughs type of adding and listing machine and the paper carriage equipment is of the same character 80 in the main as used upon this machine and as disclosed in a number of prior patents, including that to Vincent, already identified. It will therefore suffice to briefly mention familiar elements of the carriage equipment, such as the main carriage frame 17, 85 slidably mounted at the back of the machine; and the cradle 17^a, carried at the upper part of said main frame; also the rock rod G at the lower part of the carriage frame, carrying 90 a series of tabulator fingers H' for determining various columnar positions of the carriage through engagement with a notched plate H mounted upon the back panel 2 of the machine proper.

The sections of the roller platen are designated respectively A and B, the latter preferably of such length as to accommodate a wide sheet of paper, while the section A is shorter and adapted for receiving the usual 100 paper strip drawn from a roll. These platen sections are axially alined in the cradle 17^a, but capable of turning independently of each other. As the purpose is to use both platen sections together when the work in hand calls for a single platen condition, the inner heads a' and b', Fig. 4, are brought 105 close together so that the surfaces of the platen sections may be virtually continuous. Furthermore, in the interests of securing 110

perfect alinement under such a condition, the spindles or shafts of the platen sections are telescoped, thus the spindle or shaft A', to which the platen section A is secured, has a somewhat elongated inner end portion α of reduced diameter, which engages a bore of the spindle or shaft B' to which the section B is secured. Preferably the said reduced portion of the shaft or spindle A' is further reduced in diameter throughout the greater part of its length, as illustrated in Fig. 4, in order to minimize the surface machined for engaging the bore of the spindle B'.

For the purpose of coupling and uncoupling the platen sections a pin or bolt W is mounted to slide in the heads of the platen section A and project into an aperture or socket b^2 in the head b' of the platen section B. A coiled spring w' surrounding the pin or bolt between the outer head of the platen section A and a collar w^2 secured to said pin or bolt, exerts itself to enforce engagement of the pin or bolt with the aperture or socket b^2 of the head b' of the platen section B. Preferably this bolt or pin slides through a bushing w^3 which is screwed into a tapped opening in the outer head a^3 of the platen section A, which arrangement facilitates assembling, since the pin or bolt with its collar w^2 and spring w' can be put in place together with the said bushing w^3 .

It will of course be obvious that when the pin or bolt is engaged with the platen section B, as shown in Fig. 4, the two platen sections are rotatably connected so as to turn as one. This connection can be broken at will or the platen sections uncoupled by simply drawing out the bolt or pin. The latter has a head w^4 to bear against the bushing w^3 and said head is flanged as shown at w^5 to facilitate taking hold of it to draw out the pin or bolt. In order to provide for maintaining the bolt in uncoupling position it is equipped with a stud w^6 , Fig. 6, which normally seats in a radial groove w^7 in the outer end of the bushing (Fig. 7). The bolt is rotatable, so that when drawn out the said stud may be turned over a plain part of the bushing so as to prevent reengagement of the bolt with the platen section B.

Each platen section has its own line-spacing equipment comprising ratchet wheel A² (B²), pawl A³ (B³), pawl carrying arms A⁴ (B⁴), link A⁵ (B⁵) and notched and slotted plates A⁶ (B⁶). As shown in the aforesaid Vincent patent, the notched and slotted plates are secured respectively to rock shafts A⁷—B⁷ journaled in the paper carriage and forming parts of two bails comprising respectively cross-rods A⁸—B⁸, which are normally in alinement as illustrated in Fig. 5. The construction here shown further corresponds with that illustrated in the Vincent patent in that either of said cross rods is adapted to be engaged by the jaws 18^a of

the reciprocating plate 18, mounted as usual upon the back panel 2 and reciprocated by the lever 18^b, which is vibrated by the cam 18^c secured to the machine shaft 100, Fig. 2. In order to avoid the possibility of either bail cross-rod engaging over the top of said jaws, as a result of the shifting of the carriage during operation of the machine when the jaws are engaged with the other rod near the inner end thereof, I provide a lock to prevent shifting of the carriage during the operation. Thus there is pivoted to the back panel 2, Figs. 1 and 3, a short lever X having at its extremity on one side of its pivot a laterally turned portion α adapted to engage either one of two notches 17^b and 17^c formed in the under side of the main carriage frame 17. A spring w' applied to said lever on the other side of its pivot enforces engagement of the laterally turned portion α with said notches under the conditions presently to be mentioned. The reciprocating slide 18 is formed with a laterally projecting lug 18^d which engages the arm of the lever X, to which the spring w' is applied, and normally stretches that spring as shown in Fig. 1 and holds the lever X in a position where its ear α is out of engagement with the carriage altogether. It is only when the carriage adjustment is such as to bring the inner portion of one bail cross-rod or the other into engagement with the jaws 18^a that there is danger of a lock-up, due to shifting of the carriage when the bail rod is depressed by the slide 18, the other bail rod not being affected and so in a position to pass over the top of the jaws under a shifting of the carriage. Therefore I find it necessary only to employ the two notches 17^b and 17^c located to correspond with the two positions of the carriage, in one of which the bail rod A⁸ has its inner portion engaged with the jaws 18^a as shown in Fig. 3, and in the other of which the inner or adjacent portion of the other bail rod B⁸ will be engaged with said jaws. Fig. 3 illustrates the action of the latch lever X under the conditions in question. Here the carriage is in a position where the inner portion of the bail rod A⁸ is engaged by the jaws 18^a and the slide 18 is represented in its lowered position. With the lowering of that slide its lug 18^d releases the lever X so that the latter immediately becomes engaged with the notch 17^c. The square side of this notch is to the left as the machine is viewed from the rear and consequently so long as the lever is engaged with it the carriage cannot be shifted to the right, or so as to carry the bail rod A⁸ out from between the jaws 18^a and the bail rod B⁸ over said jaws.

Likewise with the carriage set in position where the inner portion of the bail rod B⁸ is engaged with the jaws 18^a depression of the plate 18 will result in the lock lever X en-

130

gaging the other notch 17^b, the square side of which is to the right as the parts are viewed from the rear and hence prevents further movement of the carriage to the left or in a direction to slide the bail rod B^b out from between the jaws 18^a and the bail rod A^a over said jaws. Of course with the completion of the operation in either case the lug 18 will act upon the lever X and unlock 10 the carriage.

I claim—

1. In a machine of the character described, the combination of a laterally shiftable carriage having a sectional paper support, 15 means applied to each section for advancing paper independently of the other section, a prime mover and connections common to the paper advancing means of both sections of the paper support, with provisions for coöperating with either to the exclusion of the other, and means for uniting the sections of the paper support at will. 20

2. In a machine of the character described, the combination of a laterally shiftable carriage having a sectional paper support, 25 bails and connections for advancing the paper, an operating member common to said bails and engageable with either while disengaged from the other, and a lock for the carriage controlled by said member. 30

3. In a machine of the character described, the combination of a laterally shiftable carriage

having a sectional paper support, bails and connections for advancing the paper, a reciprocating member engageable with either bail for operating the same independently of the other, and a carriage lock normally displaced by said member. 35

4. In a machine of the character described, the combination of a laterally shiftable carriage having a sectional paper support, bails and connections for advancing the paper, the bails having normally aligned cross-rods, a reciprocating slide with jaws to embrace either cross-rod according to the lateral position of the carriage, and a lock-lever yieldingly impelled to engagement with the carriage and normally restrained by said slide. 40

5. In a machine of the character described, the combination of a laterally shiftable carriage having a sectional paper-support and lock-notches; bails and connections for advancing the paper, the bails having normally aligned cross-rods; a reciprocating slide with jaws to embrace either cross-rod according to the lateral position of the carriage; and a lock-lever yieldingly impelled to engagement with the lock-notches of the carriage and normally restrained by said slide. 45 50 55
